CLAIM

The ornamental design for a work lamp, as shown and described.

DESCRIPTION

FIG. 1 is a perspective view of a work lamp showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a perspective view thereof shown in an alternative configuration of use with the lamp portion rotated to the handle portion; and,

FIG. 9 is a perspective view thereof shown in an alternative configuration of use with the lamp portion rotated to the handle portion and the hook rotated out.

The dashed broken lines immediately adjacent the shaded surfaces depict the bounds of the claimed design, whereas the remaining broken lines depict portions of the work lamp, all of which form no part of the claimed design. The dot-dash broken lines represent the boundaries of the claimed design, and form no part thereof.

1 Claim, 7 Drawing Sheets
